CYLINDER CASTING OR CYLINDER BLOCK
FOR STEAM ENGINES AND THE LIKE

Thomas J. Hoy, Newark, N. J.

Application September 26, 1939, Serial No. 295,782

8 Claims. (CL 121—185)

This invention relates to improvements in the cylinder valve chest and valve cage construction of steam driven locomotive engines or the like, in which the distribution of the steam is effected under the control of cam operated poppet valves which may be of the balanced or double seat type.

A primary object of the invention is to provide means to obtain true valve seatings to ensure steam tightness, regardless of distortions which may take place in the cylinder structure surrounding the said valve seatings. Such distortions may be the result of elastic deformations of the cylinder structure caused by the piston thrust or other internal stresses due to unequal expansion of the metal under the influence of temperature differentials. With this object in view, the invention is particularly useful in high capacity locomotives utilizing steam at high pressures with a high degree of superheat, in which a steam tight poppet valve is essential.

Another object of the invention is to provide mechanism to attain the foregoing advantages, which shall be positive in operation, simple in construction and readily applicable to conventional locomotives.

How I attain the foregoing, together with such other objects and advantages as are incident to my invention or will occur to those skilled in the art, will appear from the following description taken together with the accompanying drawings, in which:

Fig. 1 represents a cross section of the cylinder structure forming the object of the invention following a vertical plane passing through the steam port leading from the steam chest into the power cylinder proper.

Fig. 2 represents a cross section of the cylinder structure following a vertical plane passing through the geometric center of the said structure.

Fig. 3 represents a longitudinal section on vertical plane through the center of the inlet steam port through which the live steam is admitted into the power cylinders.

Fig. 4 represents a longitudinal section on vertical plane through the center of the exhaust port which connects the power cylinder through the exhaust passages with the exhaust nozzle in the smoke box.

Fig. 5 represents a section following a horizontal plane through the steam chest which is provided with a common branch pipe leading from the source of supply of live steam to the power cylinders.

Fig. 6 represents an enlarged detailed view of the poppet valve cage for an inlet poppet valve.

Fig. 7 represents a detailed view of the valve cage for an exhaust poppet valve.

Similar reference numbers indicate corresponding parts throughout the views in the drawings. Referring now to the drawings in detail it will be seen that for each power cylinder, two inlet poppet valves and two exhaust poppet valves are provided. Live steam is admitted through branch pipe 11 into cavities 5 and 4, whence it flows into the power cylinder. After having done its work the live steam escapes through cavity 3 to the exhaust poppet valve and then to passages 8, whence it flows to the base of the exhaust nozzle 10. It should be noted that the poppet valve can be preferably constructed along the lines of the design disclosed by the inventor's patent application bearing Serial No. 291,806, dated August 25, 1939. However, the scope of this invention is not limited to this type of poppet valve and the conventional styles can also be used. Experience with known type of poppet valve cylinders has shown that it is not always possible to maintain the trueness of the valve seatings, if the same are rigidly attached to the cylinder structure. Not only are such valve seatings likely to become distorted under the influence of uneven expansion within the cylinder casting but they also have a tendency to change their relative positions when compared with the conditions which prevail when the valves are ground in at first. Moreover, experience with a heavily pulling steam locomotive of the conventional design has shown a tendency to a certain amount of breathing within the cylinders and surrounding bed plates due to the periodical fluctuations of the piston thrust.

It is therefore obvious that valve seatings which are rigidly attached to the cylinder structure must inevitably become affected by such periodical breathing movements and steam tightness is difficult under such conditions.

By referring now to Fig. 6 it will be seen that according to the new invention, the following means eliminate the aforementioned inconveniences. Instead of having a valve cage rigidly fastened to the main cylinder structure according to conventional and known poppet valve cylinder designs, in my new invention resilient means are interposed between the valve cages and the cylinder structure. The valve cage 29 contains in one removable structure the poppet valve seatings of which the valve seat 35 is preferably made flat. The inner valve seat 36 in the case of a

double seat poppet valve arrangement is preferably made spherical to facilitate alignment and the same is connected to inlet valve cage 29 by means of ring 30, which in turn is held in position by several flat-headed screws and fluid tightness is obtained by means of a gasket 37. The connection between part 36 and part 30 is made through a metallic bellows 38. A restraining ring 27 limits the movement of part 36. A valve stem guide 25 is pressed into valve cage 29. It will be seen that the valve cage 29 is fastened to the cylinder structure by several bolts 39 in such a manner that the whole assembly can be removed and gasket 31, preferably made of asbestos, makes the attachment of the valve cage 29 to the cylinder structure resilient.

Since it is necessary to provide a fluid pressure tight seal between cavity 5 and cavity 4, when the poppet valve is in position, it is likewise essential that such a seal should be of a resilient character. Accordingly, a metallic bellows of the type 34 is interposed between the upper part of the valve cage 29 and the cylinder structure. This bellows 34 is welded in a fluid pressure tight manner on one of its extreme ends to valve cage 29 and on the other extreme end to restraining ring 33, which is pressed against a resilient gasket 28 in a fluid pressure tight manner and which is fastened to the cylinder structure by several cap screws 32.

It will no doubt be clear from the foregoing description that a change in shape of the cylinder structure, within reasonable limits, will not affect the trueness in relationship to the center bore of valve stem guide 25 of valve seats 35 and 36, since the flexible bellows 34 and the gaskets 31 and 28 are not capable of transmitting any distorting forces to the valve cage structure 29. Moreover, as will be noted from Fig. 6, the diameter of the cylindrical extension of valve cage 29 projecting into a corresponding bore in the cylinder structure is purposely kept smaller so as to render immune said valve cage against structural deformation of the cylinder.

To satisfy requirements of ease of inspection and removal, the cylinder structure is provided with a steam chest shaped to be free from obstructions on its top as will be seen in Figs. 1, 2 and 3. Suitable circular openings 6, which are located directly above the recess for the reception of inlet valve cage 29, render the problem of periodical examination of the poppet valve assembly an easy one, as all that is necessary, is to remove the inspection cover, (not shown), which is fastened in a steam tight manner to the top of the steam chest 5. Incidental to the construction as is disclosed by Fig. 6, another advantage is also obtained. The direction of flow of live steam from steam chest 5 to the power cylinder through cavity 4 is made free from sharp bends and streamlined flow of the live steam is almost possible. The valve cage 29 is provided with bridges of a comparatively small cross sectional area to impede as little as possible the flow of steam. In contrast to conventional valve cage construction in which a considerable force has to be transmitted through such bridges to effect a steam tight valve cage, in my invention no such need exists, since the only force which tends to pull the top part of the valve cage from the bottom part of the same is the axial resistance of the bellows 34, which naturally is negligible in comparison with the tensile and compression strength of the valve cage bridges. Under such conditions, the wire drawing losses of the live

steam will be reduced considerably and a gain in cylinder efficiency can be expected. As will be noted from Figs. 1 and 6, and Fig. 3 in particular, my new invention also lends itself particularly well to an easy machining operation as no close tolerances are required for the recesses which are provided for the valve cages 29. Furthermore, the problem of maintenance by roundhouse mechanics of a device built according to my invention is greatly simplified in contrast with the problem presented by known poppet valve gear designs, because after removal of the valve cage 29 from the cylinder structure, the whole assembly can be cleaned and repaired on a working bench in the roundhouse without the need of working on a more or less inaccessible cylinder block of a locomotive, which more often than not, is exposed to inclement weather conditions in the yard.

In the event of failure of a part of the valve cage assembly, a spare assembly, which may be kept in the store room, can be readily put in the place of the defective assembly without the need of fitting work necessitating the use of skilled mechanics, because the flexibility of the gasket 31 and bellows 34 and 38 will compensate for any inaccuracies of assembly.

Adhering to the principle of greatest freedom in the flow of the steam, my new invention also provides a novel method of construction of the valve cages for the exhaust poppet valve. By referring to Fig. 7, it will be seen that in accordance with the aforesaid principle, the exhaust valve cage is inverted by comparison with the construction of the inlet poppet valve cage as shown by Fig. 6. Whereas, the flow of the steam from the steam chest 5 into cavity 4, leading into the power cylinder is downward, the flow of the exhaust steam from the power cylinder through port 3 into cavity 8 which leads to the base of the exhaust nozzle 10, is taking place in an upward direction. Consequently, the whole exhaust valve cage assembly will have to be withdrawn through aperture 7 in Figs. 1 and 4 because no part thereof can be fastened to the partition wall 9 in the absence of suitable space. Here again the resilient means employed to effect a pressure tight seal between cavity 3 and 8 are similar to the ones used in the case of the inlet valve cage assembly shown by Fig. 6.

Resilient means of a similar character are employed for the exhaust poppet valves as shown on Fig. 7. Exhaust valve cage 12 is extending through aperture 7 into recess 9 of the exhaust port 3. Again it will be noted that the exhaust valve cage 12 is kept to a smaller diameter on its top portion by comparison with the corresponding aperture 7. An elastic packing 18 establishes a steam tight seal of the exhaust cavity 8 against the atmosphere. It will be evident that slight variations in shape of the cylinder structure are not likely to cause any deformations of the exhaust valve cage 12 because the elastic packing 18 will absorb any such irregularity. In order to establish a steam tight seal between the exhaust port 3 and the cavity 8 when the exhaust valve is in position, resilient means are again employed to render the exhaust valve cage immune against any possible distortions which may take place within the cylinder structure. In the described conception of my invention, metallic bellows 17 which are welded in a fluid pressure tight manner to the valve cage 12 on one extreme end and to a retaining ring 15 on the other extreme end, will serve the purpose.

The retaining ring 15 in turn is pressed against gasket 16 so as to prevent the escape of pressure steam from port 3 into cavity 8. With the view of facilitating removal of the whole assembly for inspection purposes, a specially designed tightening rod 20, which can be gripped from the outside on its top extension with a wrench, is provided. A cap 18 which is provided with a pipe thread is screwed into a corresponding recess in the top flange of the valve cage 12 to prevent any leakage of exhaust steam. Several tightening rods 20, equally spaced, will make the problem of maintaining a steam tight valve cage seal against the cylinder structure easy and no matter how carelessly these rods 20 may be tightened, no crushing of the valve cage bridges will take place by contrast with the known methods of attachment of such valve cages to their respective cylinder structures. Fig. 7 also discloses the same style of valve seat attachment for the spherical valve seat 21 as has been employed in the inlet valve cage construction. The restraining plate 22, in conjunction with metallic bellows 23, functions in a manner already disclosed by my invention in accordance with the specifications bearing Serial No. 291,806, dated August 25, 1939 in the event of a double seat poppet valve construction being adopted. Adapter piece 13 and valve stem guide 14 again have the same purpose as disclosed by the embodiment of my invention shown on Fig 6. The valve seat 23, closest to the power cylinder, is preferably flat and part of the valve cage 12. It is understood that the scope of this invention is not limited to the specific resilient means shown in this instance to render the valve cage 12 immune against deformations in the cylinder structure but covers also mechanical equivalents to the construction described.

I claim:

1. In cylinder structure for transmission of power to the main driving wheels of steam locomotives or the like, of the character described, in which the distribution of the steam is effected under the control of cam operated poppet valves of the double seat type, comprising inlet poppet valve cages and exhaust poppet valve cages for each power cylinder, means to render such valve cages immune against distortions within the cylinder structure.

2. In cylinder structure for transmission of power to the main driving wheels of steam locomotives or the like, of the character described, in which the distribution of the steam is effected under the control of cam operated poppet valves of the double seat type, comprising inlet poppet valve cages and exhaust poppet valve cages for each power cylinder, means to render such valve cages immune against distortions within the cylinder structure, said means being attached in a fluid pressure tight manner to the valve cages and the power cylinder structure respectively.

3. In cylinder structure for transmission of power to the main driving wheels of steam locomotives or the like, of the character described, in which the distribution of the steam is effected under the control of cam operated poppet valves of the double seat type, comprising inlet poppet

valve cages and exhaust poppet valve cages for each power cylinder, means to render such valve cages immune against distortions within the cylinder structure, said means consisting of metallic bellows of the Sylphon type.

4. In cylinder structure for transmission of power to the main driving wheels of steam locomotives or the like, of the character described, in which the distribution of the steam is effected under the control of cam operated poppet valves of the double seat type, comprising inlet poppet valve cages and exhaust poppet valve cages, said cages being attached in a resiliently steam tight manner to the surrounding parts of the cylinder structure through metallic bellows and detachable retaining rings to permit removal of said poppet valve cages together with said resilient means from the cylinder structure in one unit.

5. In cylinder structure for transmission of power to the main driving wheels of steam locomotives or the like, of the character described, in which the distribution of steam is effected under the control of cam operated poppet valves of the balanced or nearly balanced type, comprising inlet poppet valve cages and exhaust poppet valve cages for each power cylinder, means to render such valve cages immune against distortions within the cylinder structure.

6. In cylinder structure for transmission of power to the main driving wheels of steam locomotives or the like, of the character described, in which the distribution of steam is effected under the control of cam operated poppet valves of the balanced or nearly balanced type, comprising inlet poppet valve cages and exhaust poppet valve cages for each power cylinder, means to render such valve cages immune against distortions within the cylinder structure, said means being attached in a fluid pressure tight manner to the valve cages and the power cylinder structure respectively.

7. In cylinder structure for transmission of power to the main driving wheels of steam locomotives or the like, in which the distribution of steam is effected under the control of cam operated poppet valves of the balanced or nearly balanced type, comprising inlet poppet valve cages and exhaust poppet valve cages for each cylinder, means to render such valve cages immune against distortions within the cylinder structure, said means consisting of metallic bellows.

8. In cylinder structure for transmission of power to the main driving wheels of steam locomotives or the like, of the character described, in which the distribution of steam is effected under the control of cam operated poppet valves of the balanced or nearly balanced type, comprising inlet poppet valve cages and exhaust poppet valve cages, said cages being attached in a resilient and steam tight manner to the surrounding parts of the cylinder structure by means of metallic bellows and detachable retaining rings to permit removal of said poppet valve cages together with said poppet valve cages and said resilient means from the cylinder structure.

THOMAS J. HOY.
